HAROLD E. SLADE, OF GLEN RIDGE, NEW JERSEY, ASSIGNOR TO BEAVER MACHINE & TOOL CO. INC., OF NEWARK, NEW JERSEY.

ELECTRIC SWITCH.

Application filed November 11, 1926. Serial No. 147,640.

So far as I am aware it has been customary up to the present time to provide small electric switches such as used in canopies or wall bracket fixtures with a removable turn 5 button or knob for manipulating or actuating the switch. The drawback to this form of actuating member is the possibility of the loss of the knob and the inconvenience caused therefrom and also it is a relatively 10 more costly arrangement than that covered by my present invention which consists of producing the actuating member in one piece. It is simple, economical, practical, and has artistic merit.

15 One object of the present invention is to provide a unitary construction of insulating material replacing a plurality of metal pieces i. e. in replacing the bakelite key which in itself contains a steel insert (two 20 parts) and then it also replaces the knurled brass button which must be used in connection with the molded bakelite key.

A further object is to provide a unitary spindle or actuating key and button combined and manner of assembly of same, the entire piece being of molded, insulating material.

In describing my invention, reference is directed to the drawing which forms a part 30 of this specification, in which:

Fig. 1, is a cross sectional elevation through the electric switch and shows the actuating member in position within the switch.

35 Fig. 2, is a plan view of the switch with cover and insulating plate removed.

Fig. 3, is a view of the actuating member or key.

Fig. 4, is a plan view of Fig. 3.

40 For the purpose of illustrating my invention I have shown in the accompanying drawings one form thereof which is at present preferred by me, since the same has been found in practice to give satisfactory and 45 reliable results, although it is to be understood that the various instrumentalities of which my invention consists can be variously arranged and organized and that my invention is not limited to the precise arrangement and organization of the instrumentalities 50 as herein shown and described.

Referring to Fig. 2, 1 is a base or body member of the switch and generally made

of an insulating material such as porcelain or bakelite and other compounds.

The base 1 is recessed as at 2, the perpendicular sides of which are in the form of cam surfaces 3, 3^a, 3^b, and 3^c; midway between the cavity 2 and the extreme ends of the base are cavities 4 and 4^a. Separating 60 the cavities 2, 4, and 4^a are projections 5, 5^a, 5^b, and 5^c forming passages 6 and 6^a. Adjacent the ends are projections 7, 7^a, 7^b, and 7^c forming passages 8 and 8^a.

Associated with the base 1 are lead wires 9—9^a to which terminals 10 are attached. These terminal ends are formed into cam shaped contacts 10^a which match with and are held against surfaces 3^a, 3^b, of the base member 1. The end of the terminals 70 through which the lead wires 9—9^a pass are formed into a U shaped member 11 and clinched over the wire. The U-shaped member 11, and the contact members 10^a are connected by a bridge member 12.

The terminals are held from lateral movement in the base by interlocking means. The U-shaped members 11 are held in cavities 4—4^a; the cam shaped surfaces 10^a are held against surfaces 3^a—3^b; and the connecting 80 or bridge members 12 are held in passages 6—6^a.

An S-shaped rotatable contact 13, is provided for opening and closing the circuit through the coaction of the shaft 14 which is made of insulating material. This shaft has a slotted section 14^a, a bearing section 14^b, and a knurled or grip section 14^c; between the slotted section 14^a, and the bearing section 14^b, is a shoulder 14^d.

By rotating the shaft 14 in a clockwise direction, the outer ends 13^a of the S-shaped contact will alternately be in contact with the surfaces 3—3^c of the base and the surfaces 10^a of the fixed contacts 10, every quarter revolution thus opening and closing the circuit twice for each full revolution of the shaft. The shaft 14 turns within a threaded sleeve 15, which is staked to a cover plate 16. This cover plate is insulated from the current carrying parts by a plate insulator 17 and the parts are held together by screws 18 passing through the base 1 and into threaded holes in the cover plate 16. A nut 19 is provided for fastening the switch to a 100 bracket.

The feature of the one piece shaft 14 is that it may be assembled within the sleeve 15 from the bottom or underside of the cover plate 16 and is prevented from being withdrawn after the switch is assembled by the shoulder 14^a, which is of such diameter as to rest against the lower end of the sleeve 15.

As the end 14^a is knurled or milled it may be readily gripped between the fingers and 10 easily rotated to actuate the moving contact. A further feature is that no further assembling of a thumb and finger knob is necessary after the switch is mounted on the fixture.

15 It will now be apparent that I have devised a novel and useful construction which embodies the features of advantage enumerated as desirable in the statement of the invention and the above description and while 20 I have in the present instance shown and described the preferred embodiment thereof which has been found in practice to give satisfactory and reliable results, it is to be understood that the same is susceptible of 25 modification in various particulars without departing from the spirit or scope of the invention or sacrificing any of its advantages.

What I claim is:

1. In a canopy switch, a base, stationary 30 and movable contacts therein, an integral actuating member comprising a bottom portion adapted to receive said movable contact, an upper handle portion, an intermediate cylindrical bearing portion, and a shoulder juxtaposed to the bottom portion of said actuating member, a cover terminating in a hollow sleeve through which said actuating member extends and in which said bearing portion thereof is journaled; said shoulder abutting 35 against the underside of said cover to prevent axial displacement of said actuating member, the outer portion of said actuating member projecting an appreciable distance beyond said sleeve, an insulating plate arranged between said base and cover, and means for securing said base, insulating plate and cover together.

2. In a canopy switch, a base, stationary 50 contacts therein, an S-shaped movable spring contact therein, an integral actuating member comprising a bottom portion having a slot to receive said movable spring contact, an upper handle portion, an intermediate cylindrical bearing portion, and an annular shoulder juxtaposed to the bottom of said actuating member, said slot terminating immediately adjacent said shoulder, a cover terminating in a hollow sleeve through which said actuating member extends and 55 in which said bearing portion is journaled; said shoulder abutting against the underside of said cover to prevent longitudinal displacement of said actuating member, the outer portion of said actuating member projecting an appreciable distance be-

yond said sleeve, an apertured insulation, plate arranged between said base and cover, said shoulder having a bearing in said insulating plate, and means for securing said base, insulating plate and cover together. 70

3. A rotary switch, including a housing, oppositely disposed stationary contacts therein in electrically insulated relation to each other, a movable contact intermediate of said stationary contacts, an apertured cover superimposed upon said housing to enclose the same, and an integral actuating spindle of insulating material extending through said cover, operatively engaging said movable contact and having a shoulder for retaining 80 said spindle against axial displacement.

4. A rotary switch comprising a housing and a closure therefor; stationary contacts therein in electrically insulated relation to each other, a movable contact operatively 85 interposed between said stationary contacts having a contacting and a non-contacting position relative to said stationary contacts, an actuating spindle of insulating material having an inner portion operatively engaging said movable contact having an outer handle portion extending beyond the housing, and having a shoulder intermediate of said housing and closure, coacting therewith to retain said spindle against axial displacement. 95

5. A switch of the character stated, including a two-part housing, stationary contacts therein in electrically insulated relation to each other, a movable contact therein disposed in operative relation to said stationary contacts and having a contacting and a non-contacting position relative thereto, an integral actuating spindle of insulating material extending into said housing and having an inner portion operatively engaging said movable contact, an outer handle portion, and having a shoulder intermediate of the two parts of said housing coacting therewith to retain said spindle against 100 axial displacement. 105

6. A switch of the character stated, comprising a two-part housing; one of said housing parts being apertured and having an elongated external sleeve surrounding the 110 aperture thereof, and externally threaded, stationary contacts within said housing in electrically insulated relation to each other, a movable contact member within said housing disposed in operative relation to said 115 stationary contacts and having contacting and non-contacting positions relative thereto, an integral actuating spindle of insulating material extending through and journaled in said external sleeve, having an inner 120 slotted portion operatively engaging said movable contact, an outer handle portion extending beyond the sleeve and having an annular shoulder intermediate of the two 125 parts of the housing and coacting therewith 130

to retain said spindle against axial displacement.

7. A switch of the character stated, including a two-part housing, stationary contacts therein in electrically insulated relation to each other, a movable contact member therein disposed in operative relation to said stationary contacts and having a contacting and a non-contacting position relative thereto, an integral actuating spindle of insulating material extending into said housing, having an inner slotted portion operatively engaging said movable contact by the seating of the latter in said slot of the former, having an outer handle portion and having means integral therewith disposed intermediate of the two parts of said housing and coacting therewith to retain said spindle against axial displacement.
8. A switch of the character stated, including a two-part housing, comprising an insulating base and an apertured metallic closure therefor, stationary electrical contacts disposed within said base in electrically insulated relation to each other, a movable electrical contact disposed within said base in operative relation to said stationary contacts and having a contacting and a non-contacting position relative thereto, an externally-threaded bearing sleeve carried by said metallic closure in alignment with the aperture thereof, an integral actuating spindle of insulating material extending through said sleeve and journaled therein, having an inner slotted portion operatively engaging said movable contact, having an outer handle portion extending beyond the sleeve and having a laterally extending annular flange beneath and immediately adjacent to said metallic closure, and coacting therewith to retain said spindle against an outward axial displacement thereof, and an apertured insulating plate intermediate of said base and metallic closure of the housing.

HAROLD E. SLADE.
